D. F. CURTIN,
PAPER CUP HOLDER,
APPLICATION FILED FEB. 29, 1912.

1,197,269.

Patented Sept. 5, 1916.

UNITED STATES PATENT OFFICE.

DAVID F. CURTIN, OF CHICAGO, ILLINOIS.

PAPER-CUP HOLDER.

1,197,269.

Specification of Letters Patent. Patented Sept. 5, 1916.

Application filed February 29, 1912. Serial No. 680,694.

To all whom it may concern:

Be it known that I, DAVID F. CURTIN, a citizen of the United States, and a resident of Chicago, in the county of Cook and State 5 of Illinois, have invented an Improved Paper-Cup Holder, of which the following is a specification.

My invention is an improvement in sanitary paper cup holders, and has for its object, the provision of a simple inexpensive device of the character specified by means of which cups or receptacles of paper may be held during their use.

In the drawings: Figure 1 is a perspective view of the improvement with the cup in place, Fig. 2 is a side view; Fig. 3 is a section on the line 3—3 of Fig. 2 looking in the direction of the arrows; Fig. 4 is a plan view of the paper sheet from which the cup 20 is formed; and, Fig. 5 is a perspective view of the formed cup, separated from the holder; and, Fig. 6 is a plan view of another form of cup sheet.

The present embodiment of the invention 25 comprises a conical holder 1, of sheet material, as for instance tin, or other suitable metal, the said holder being formed from a substantially semi-circular sheet, bent into form.

30 The holder is split from top to bottom, and the edges of the split are bent outwardly to form a flange 2 at each edge, the said flanges extending radially and being substantially parallel with each other. The 35 upper edge of the holder is beaded, as indicated at 3.

It will be noticed that adjacent to the holder, the flanges 2 are close together, and diverge slightly from each other toward 40 their free edges. A plate or strip 4 is arranged on the outer face of each flange, the plates being of somewhat greater length than the flanges, so as to extend above the same, as shown in Fig. 2, and each plate is 45 provided with a longitudinal groove on its inner face forming a longitudinal rib 5 on its outer face.

A split tube 8 is provided for normally holding the flanges 2 clamped on the edges 50 of the cup, and for holding the plates 4 in place on the flanges. The tube is slipped over the plates, with the edges 9 of the split engaging between the ribs 5 and the body of the holder. The said tube is resilient, and 55 by its pressure against the plates 4, clamps the flanges 2 together. A means for separating

the flanges is provided, the same comprising lateral lever arms 6 which are preferably formed integrally with the plates 4, as shown in Fig. 3. The tube 8 is provided with slots or openings 10 through which 60 said arms project, the inner edges of the slots serving as fulcra for the arms. A finger-piece in the form of a disk 7 is secured to the outer end of each arm. By 65 pressing the disks 7 toward each other, the plates 4 will be separated or opened more or less, corresponding to the pressure, and the flanges 2 of the split tube 8 will be also separated so as to release the cup. The slots 10 70 in the split tube have less diameter than the disks 7, so that the tube 8 cannot be detached from the plates 4, after the disks have been duly attached. The ribs 5 hold the tube in place, as will be readily understood. The 75 parts of the device are assembled as follows: The tube 8 is slipped over the ribs 5 of plates 4 and disks 7 then attached to the arms 6. One of the lever arms 6 is offset inwardly, as shown at 11, in Fig. 3, to limit the movement of the arms toward each other. 80

The cup is formed from a sheet 12 of paper, cut to substantially semi-circular shape, as shown in Fig. 4. The sheet is placed in the holder 1 with the curved edge 13 substantially parallel with the beaded edge 3 of the holder, as indicated in Figs. 1 and 2. When so placed, the edge 14 of the sheet is doubled upon itself to form flaps 15, which extend between the flanges 2 of the 90 holder. While placing the sheet, the disks 7 are pressed toward each other, to spread the tube 8, and to relax the pressure on the plates 4, which permits the flanges 2 to separate. As soon as the sheet 12 has been so 95 placed, the pressure on the disks 7 is relaxed and the tube clamps firmly on the flaps.

The sheet 12 is somewhat greater than a semicircle, the excess portion being shown below the dotted line in Fig. 4. The said 100 line indicates the fold of the flaps 15. The completed cup is shown in Fig. 5, and it will be noticed that the flaps 15 are continuous at the bottom of the cup, as indicated at 16, and this portion of the sheet is pressed 105 tightly together with the flaps 15, so that the cup is water tight.

After using the cup, the sheet may be removed, by pressing the plates 7 together or toward each other. Each lug 6 when the 110 plates are pressed together, fulcrums upon that portion of the tube between the slots to

spread the tube. After the tube is so spread, that portion of the sheet projecting above the edge of the holder may be grasped to remove the sheet from the holder. The said portion is designed to prevent the lips from touching the holder.

While a sheet of the form shown in Fig. 4 is preferable, it is obvious that the cup might be formed from a simple rectangular sheet, or from any other desired shape. The rectangular form is preferable when cost is a consideration, and the sheets may be supplied in the same manner as is toilet paper, that is in a roll, the individual sheets being separated by partially separating the strip of paper at spaced intervals.

It is obvious that cups of many different shapes may be formed depending upon the shape of the holder. For instance, shallow cups may be provided with a holder shaped to suit for holding ice cream or the like. For making cups, the sheet is preferably of the shape shown in Fig. 6, that is approximately three fourths of a circle. The said sheet 17 has a segment of approximately one fourth cutaway, and that portion 18 of the sheet below the dotted line 19 corresponds to the portion 14 of the sheet shown in Fig. 4. That is, the said portion 30 forms the flaps. It will be noted that each end of the said portion is cutaway or

notched, as at 18. A holder for making cups from the sheets shown in Fig. 6, would be shaped like the holder shown in Fig. 2, with the exception that the cone would be of 35 lesser depth.

I claim:

1. In a device of the kind described, a cup holder of conical form having a longitudinal slit in its wall and the edges of said holder 40 at said slit projecting laterally, in combination with a spring clamp arranged to press upon said projecting edges and normally hold the edges of said slit together, and means for manually releasing the pressure 45 of said clamp.

2. In a device of the kind described, a cup holder of conical form having a longitudinal slit in its wall and with the edges of said holder at said slit projecting laterally, 50 in combination with a spring clamp arranged to press upon said projecting edges and normally hold the edges of said slit together and a pair of projecting arms upon said clamp adapted to serve as a handle for said holder and for manually releasing the pressure of said clamp. 55

DAVID F. CURTIN.
